UNITED STATES PATENT OFFICE.

SOPHUS SAMSON, OF CHICAGO, ILLINOIS.

DESIGN FOR A SIGN.

No. 39,710.

Specification for Design.

Patented Dec. 22, 1908.

Application filed July 3, 1908. Serial No. 441,927. Term of patent 7 years.

To all whom it may concern:

Be it known that I, SOPHUS SAMSON, a citizen of the United States, residing at Chicago, in the county of Cook and State of Illinois, have invented a certain new, original, and ornamental Design for Signs, of which the following is a specification, reference being had to the accompanying drawing, forming a part thereof.

The figure on the drawing is a perspective view of a sign showing my new design.

I claim:

The ornamental design for a sign, as shown.

SOPHUS SAMSON.

Witnesses:

JAMES R. OFFIELD,
M. E. ADAMS.
